UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

KNOCKDOWN RENEWABLE WASHING-CYLINDER.

1,105,174.

Specification of Letters Patent. Patented July 28, 1914.

Application filed May 28, 1913. Serial No. 770,460.

To all whom it may concern:

Be it known that I, WILLIAM BARTHOLOMEW, a citizen of the United States, residing at Chicago, in the county of Cook and State of Illinois, have invented certain new and useful Improvements in Knockdown Renewable Washing-Cylinders, of which the following is a specification, reference being had therein to the accompanying drawing.

10 This invention relates to certain new and useful improvements in washing cylinders and has for its object, the provision of a knock-down renewable washing cylinder which is so constructed that the same can be readily taken apart and packed for shipping and one which when set up, can be readily repaired such as by the replacing of a stave or any parts thereof very readily.

Another object of the invention is to provide a washing cylinder having metal heads and head plates carrying the ribs and staves which are so mounted that when the staves and ribs swell by the action of the water, an exceedingly tight joint will be formed between the heads, staves and ribs in order to prevent leakage and injury to the goods being washed.

A further object of the invention is to provide a washing cylinder with metal heads in order to prevent the same from swelling by the action of the water in order to maintain the cylinder in proper form at all times, so that the same will be perfectly balanced in order to allow the same to rotate freely.

35 Another object of the invention is to provide an improved construction of hoop tightening means for holding the staves and ribs in position upon the heads in such a manner that by loosening the tension means, a stave or rib can be readily removed and a new one inserted.

Another and still further object of the invention is to provide novel means for connecting the trunnion plates to the heads, whereby the two will be interlocked together in order to relieve the strain upon the connecting bolts.

50 Other and further objects and advantages of the invention will be hereinafter set forth and the novel features thereof defined by the appended claims.

In the drawings—Figure 1, is a perspective of a washing cylinder constructed in ac-

cordance with my invention; Fig. 2, is a longitudinal section through an end portion 55 of the same showing the manner of mounting the staves on the head plate and the connection between the trunnion plate and head; Fig. 3, is a detail longitudinal section through the cylinder showing the manner 60 of mounting the rib and the connection between the rib and head plate; Fig. 4, is a detail section through a portion of the head and trunnion plate showing the interlocking lugs and the bolt for connecting the 65 same; Fig. 5, is a detail side elevation showing the hoop tightening means for placing the head under tension; Fig. 6, is a plan of the head detached; Fig. 7, is a detail of a portion of the head plate showing the notch 70 formed therein which co-acts with the kerf of the rib; Fig. 8, is a detail enlarged section through one of the ribs and adjacent staves showing the kerfs formed therein to receive the head plate; Fig. 9, is a detail section showing the rabbet of the rib to receive the stave of the door; and Fig. 10, is a detail section showing the latch for holding the door in closed position.

Like numerals of reference refer to like 80 parts in the several figures of the drawings.

In carrying out my improved invention, I employ a pair of heads 1 formed exactly alike, the description of one being sufficient for both; each head comprising a hub portion 2 having radiating therefrom, spokes 3 terminating in sockets 4 for the purpose hereinafter fully described. The spokes are connected together by an intermediate rim portion 5 whereby a complete head is formed 85 90 of a casting. The rim portion of the casting is enlarged as shown at 6 having a central depression 7 which is apertured as shown at 8 and in the form of casting herein shown.

The hub 2 of the head 1 is provided with a plurality of circular sockets 9 having threaded bores as shown at 10 into which are adapted to extend the co-acting circular projections 11 of the trunnion plate 12 which 100 is provided with a trunnion 13 secured therein in any suitable way, but herein shown mounted and fixed within a hub portion 14. The projection 11 is provided with an aperture 15 registering with the bore 10 of the 105 corresponding socket 9 into which a screw

bolt 16 is adapted to extend for securely locking the trunnion plates in position upon the heads.

Mounted within the rib sockets 4 are ribs 5 17 having reduced ends 18 which are seated within the sockets 4 and are secured therein by bolts 19 extending through the ribs and apertures formed in the bottoms of the sockets 4 so as to securely lock the ribs to the heads. The spokes 3 are enlarged as shown 10 at 20 in order to allow the bolts to be readily manipulated by a suitable tool.

Arranged on the rim portions 5 between the ribs are perforated staves 21, the ends of 15 which are reduced forming shoulders to prevent longitudinal movement between the heads, and it will be seen that the reduced portion of the ribs also prevents longitudinal movement of the ribs between the heads 20 and as shown in the drawing, the ribs are of greater thickness than the staves in order to form an exceedingly strong cylinder, the reduced portions at the ends of the ribs and staves being in proportion in order to form a 25 smooth exterior and interior to the cylinder. The staves are secured in position upon the rim by rivets or bolts 22 as herein shown, but as will be later described, these are not essential as I provide means for securing the 30 staves upon the rim without directly fastening each stave which will securely hold the staves in position.

Arranged within the cylinder against each head is a head plate 23 preferably formed of 35 brass having peripheral notches 24 adapted to embrace the inwardly projecting portions of the ribs 17; said inwardly projecting portions of the ribs being kerfed as shown at 24' to receive the marginal edge of the notch 40 of the head plate. The staves 21 are also kerfed adjacent the shoulder formed by the reduced portion as shown at 25 to receive the peripheral edge of the head plates 23 and it will be seen that by this manner of mounting 45 the staves and ribs upon the head plate, the head plate will be embedded within the staves and ribs so that when the wood swells by the action of the water, an exceedingly tight joint will be formed between the head 50 plates, staves and ribs in order to prevent any leakage, and at the same time to form an exceedingly smooth joint so as to prevent injury to the goods being washed.

Arranged over the staves and ribs at each 55 end of the cylinder, is a hoop 26 provided with an aperture in which is mounted a bolt 27 adapted to extend through the aperture 8 of the depression 7 of the enlarged portion 6 of the rim; said bolt carrying a nut 60 28 by means of which, the portion of the hoop over the depression 7 can be drawn within the depression in order to place the hoop under tension so as to securely hold the same in position upon the cylinder, and it 65 will be seen by this manner of connecting

the hoop to the cylinder, the tension can be readily removed in order to allow the hoop to be detached so as to remove a rib or stave in order to replace the same by a new one.

By providing a cylinder with hoops having tightening devices as shown, all projections are dispensed with and means is provided for placing the binding hoops under tension quickly and in such a manner that the hoops can be readily placed in position or detached therefrom. The enlarged portion 70 6 of the heads are of such a size that the peripheral edge thereof will be flush with the outer faces of the ribs and staves, and arranged between these enlarged portions is a door 29 which is connected to one of the adjacent ribs by hinges 30 and the free edge thereof is seated in a rabbet 31 formed in the opposite rib as clearly shown in Fig. 9, in order to form a tight joint between the edges of the door and the cylinder. The door 29 is formed of perforated staves and a non-perforated stave which are carried by hoop sections as shown, the end 75 32 being formed double by bending the same so as to form a space for receiving the staves and terminating in projecting ends 33 which engage the outer faces of the rabbeted rib. The cylinder is provided with a central hoop 34 terminating at 80 the edge of the door opening as clearly shown in Fig. 1, in order to strengthen the ribs and staves. The door is provided with a latch 35 at one end adapted to co-act with the adjacent hoop so as to lock the door when 85 it is forced into closed position and the latch is preferably formed of a bolt having a projection 36 for operating the same.

From the foregoing description, it will be seen that I have provided a washing cylinder 90 in which metal heads are formed for the wooden staves and ribs which can be held in position thereon without the use of bolts by the tension hoops but in exceedingly large cylinders, it is necessary to secure the staves 95 by bolts as shown in the drawing. But, I do not wish to limit myself to the securing of the staves to the rim of the head, as I have found that under ordinary conditions, the staves will be held in their proper position 100 as they are prevented from moving longitudinally in either direction between the heads and that by fastening the ribs in the rib sockets of the heads by bolts, a cylinder is formed which is exceedingly strong and 105 durable.

I claim:

1. A knock-down washing cylinder comprising heads provided with detachable trunnions, said heads being provided with 110 rib sockets, ribs connecting said heads seated in said sockets, bolts extending transversely through said sockets and ribs, staves arranged between said ribs, and hoops surrounding said ribs and staves.

2. A washing cylinder, comprising a head connected together by staves and ribs, said head being provided with radial enlarged portions, a door working between said enlarged portions, hoops surrounding said staves and ribs, and head plates arranged against said head members embedded within said staves and ribs. 35
3. A knock-down washing cylinder having head plates provided with rib sockets, ribs arranged in said sockets, bolts for securing said ribs within said sockets, staves provided with shoulders arranged between said heads, said staves and ribs being provided with kerfs, head plates arranged adjacent said heads having their peripheral edges extending into the kerfs of said staves, said head plates being provided with notches, the marginal edges of which extend into the kerfs of said ribs, and hoops surrounding said staves and ribs. 40
4. A washing cylinder having wooden ribs and staves provided with kerfs, and metal head plates arranged within said kerfs. 45
5. A knock-down washing cylinder comprising a pair of heads having channel spokes terminating in rib sockets and provided with enlarged portions adjacent the rib sockets, ribs having reduced ends seated in said sockets, staves having reduced ends seated upon the rim of said head, metal head plates arranged within said staves and ribs 50
- adjacent the heads of said cylinder and embedded therein, and hoops surrounding said ribs and staves. 55
6. In a washing cylinder, the combination with head members, of head plates, ribs and staves connecting said head members having kerfs to receive said head plates, and hoops surrounding said ribs and staves. 60
7. A wooden washing cylinder having metal heads embedded in the staves and ribs thereof, and hoops surrounding said ribs and staves having means for placing said hoops under tension. 65
8. A washing cylinder comprising heads provided with rib sockets, ribs seated in said sockets and extending below the bottom thereof, said ribs being provided with kerfs upon their lower end and sides, staves arranged on said head members between said ribs, metal head plates having their peripheral edges arranged within the kerfs of said staves, said head plates being provided with notches embracing said ribs and extending into the grooves thereof, and hoops surrounding said ribs and staves. 70

In testimony whereof I affix my signature in presence of two witnesses.

WILLIAM BARTHOLOMEW.
